UNITED STATES PATENT OFFICE

ROBERT N. INGERSOLL, OF LONGMEADOW, MASSACHUSETTS, ASSIGNOR TO MILTON
BRADLEY COMPANY, OF SPRINGFIELD, MASSACHUSETTS, A CORPORATION OF MASSACHUSETTS

DESIGN FOR A CRAYON LABEL

Application filed February 26, 1932. Serial No. 43,008. Term of patent 7 years.

To all whom it may concern:

Be it known that I, ROBERT N. INGERSOLL, a citizen of the United States, residing at Longmeadow, in the county of Hampden and State of Massachusetts, have invented a new, original, and ornamental Design for Crayon Labels, of which the following is a specification, reference being had to the accompanying drawing, forming part thereof.

The figure is a plan view of a crayon label, the lower right hand corner being broken away to provide space for signature, showing my new design.

I claim:

The ornamental design for a crayon label, as shown.

ROBERT N. INGERSOLL.
